RETAINING DEVICE FOR PNEUMATIC DRILLS

Victor Karl Nelson, Glen Afton, Ontario, Canada

Application July 18, 1938, Serial No. 219,810

8 Claims. (Cl. 279—19.3)

My invention appertains in particular to rock drills of the drifter and sinker types in which a steel is worked by the impacts of blows delivered to it by a pneumatically actuated piston.

5 My invention has for its object to provide an efficient and serviceable retaining device in the chuck by which the steel can be keyed at will in order that it may be readily withdrawn from a hole. A manual control is supplied on the front 10 head by which the user can effect the keying of the steel by depression of a keeper and release the steel by retracting the keeper.

The invention provides a mechanism that 15 operates to firmly wedge the steel in the drill while in action and facilitate its removal from a hole in which it has become lodged.

In the accompanying drawing, Figure 1 is a fragmentary elevation, partly in section, of a drilling machine incorporating the invention. 20 The view shows the front head portion.

Figure 2 is a front end view thereof.

Figure 3 is a cross section taken on line 3—3 of Figure 1 depicting the retaining device in its released position.

25 Figure 4 is a similar section but depicting the retaining device in its locked position.

Figure 5 is a detail cross section taken on line 5—5 of Figure 3 showing the mounting of the keeper.

30 Figure 6 is an elevation of the chuck.

Figure 7 is a view of a section of the steel and a key that engages a keyway provided in it.

Figure 8 is a view of the keeper.

35 Like numerals of reference designate similar parts in each figure of the drawing.

The usual front head of the machine is generally denoted at 9 and is shown as equipped with the buffer springs 10, of which the rods 11 secure it to the cylinder 12. The chuck 13 rotates in the front head in customary manner in 40 the operation of the machine. The steel 14 is of a polygonal cross section and is inserted in a similar shaped bore of the chuck. The unshanked steel abuts the anvil block, not shown, as will be well understood.

45 In carrying out the invention, the shouldered annulus 15 on the chuck, that is made a running fit in the bore of the front head, is supplied with a radial key slot 16 leading inwardly to the bore transversely of one of the flats thereof. A keyway or notch 17 is furnished in the steel for registry with said slot. The outer part of the slot is abruptly widened circumferentially of the chuck, presenting a general T-shaped opening in cross section defined by the face 16a

at right angles to the radial extent of the slot. The face is drilled at each side to provide recesses 18.

A key 19 is slidably fitted in the slot and formed with wings 20 that overlie the recesses 18. The wings present inner shoulders engaged by compression springs 21 seated in the recesses 18. The wings are shown as equipped with pilots 22 engaged in the springs.

The back 23 of the key is curved to conform 10 to the curvature of the bore of the front head, and is supplied with a medial ball seat 24 in the nature of a spherical depression. The seat is receptive to a hardened steel ball 25. The springs 21 function to urge the key outwardly, as will be 15 apparent, and normally hold it against the bore of the front head as is shown in Figure 3. The key in this position is clear of the bore of the chuck and therefore is disengaged from the keyway 17.

The ball is used to wedge the key in an advanced position, as shown in Figure 4, and for this purpose a boss 26 is fashioned on the front head with a radial hole 27 in alignment with the seat 24. A keeper 28 is fitted in the boss and consists of a shank slidably endwise in the hole and a flat head by which it can be slid and turned by hand. The keeper is supplied with means to lock it in both an inner and an outer position. The means consist of a nodule 29 formed on the shank 25 and slidable in a groove 30 in the wall of the hole 27. At the inner end of the groove is a circumferentially extending recess 31, and at the outer end is a similar recess 32. The grooved 30 part of the hole is thus supplied with a double 35 bayonet slot.

By pushing the keeper inwardly and giving it a part turn, it is secured in one position by reason of the engagement of the nodule in the recess 31. Upon release it can be pulled outwardly and turned to likewise lock it in the other position. The groove extends to the end of the boss which is furnished with a screw cap 33 for assembly 40 of the ball and the keeper. When the keeper is in its inner position the end face 34 of its shank 45 is flush with the bore of the front head, and when it is shifted to the outer position the hole accommodates the ball. The keeper is made of steel and preferably magnetized to attract the ball so that in its normal outer position the ball 50 is retained in the hole to which it has access.

In the operation of the machine, when it is required to use the retaining device the keeper 28 is inwardly urged and so soon as the ball contacts the key the latter is shifted inwardly into 55

engagement with the keyway 17. As the chuck revolves, the ball drops into the seat 24 and in the continued rotation is carried around with the chuck in contact with the bore of the front head 5 which constitutes a race-way for it. Since the steel is now retained, the mounted machine in being fed backwards by the crank of the mount will withdraw the steel with it. Upon withdrawal, the retaining device is released by shifting the 10 keeper to its outer position which permits the ball to resume its normal position in the hole 27.

It is manifest that the retaining device is applicable to different classes of drilling machines such as stoppers, liners, sinkers, or pluggers. 15 Moreover, such modifications and changes may be made as come within the spirit and scope of the appended claims.

I claim:

1. The combination in a pneumatic drill, of a 20 front head having its bore interrupted by a hole, a chuck journalled in said bore and having an axial bore receptive to a steel, a depressible key mounted in said chuck in alignment with said hole for retaining said steel, a loose element normally confined in said hole and adapted to be urged into the bore of said front head to depress said key, means for effecting such displacement of said element, and means retaining said element against dislodgment from said key whereby 25 said element is carried around the bore of the front head in the rotation of the chuck.

2. The combination in a pneumatic drill, of a front head having its bore interrupted by a hole, a chuck journalled in said bore and having an 30 axial bore receptive to a steel, a depressible key mounted in said chuck in alignment with said hole for retaining said steel, a ball normally confined in said hole so as to be urged into the bore of said front head to depress said key, means for effecting such displacement of said ball, and means retaining said ball against dislodgment 35 from said key whereby said ball is carried around the bore of the front head in the rotation of the chuck.

45 3. The combination in a pneumatic drill, of a front head having its bore interrupted by a hole, a chuck journalled in said bore and having an axial bore receptive to a steel, a depressible key mounted in said chuck in alignment with said 40 hole for retaining said steel, said key having a depressed seat for registry with said hole, a ball normally confined in said hole so as to be urged into the bore of said front head to engage said seat and depress the key, and means for effecting 45 such displacement of the ball from the hole whereby it is caused to travel around the bore of the front head in the rotation of the chuck to maintain the key in depressed position.

4. The combination in a pneumatic drill, of a 60 front head having its bore interrupted by a hole, a chuck journalled in said bore and having an axial bore receptive to a steel, a key radially slidible in the chuck for engaging a keyway in said steel when inwardly depressed, said key having a depressed seat for registry with said hole, a spring outwardly urging said key, a ball normally confined in said hole so as to be urged into the bore of said front head to engage said seat and depress the key, and means for effecting such 65 placement of the ball from the hole whereby it is caused to travel around the bore of the front

head in the rotation of the chuck to maintain the key in depressed position.

5. The combination in a pneumatic drill, of a front head having its bore interrupted by a hole, a chuck journalled in said bore, a steel inserted in said chuck and having a keyway in alignment with said hole, a key radially slidible in said chuck for engaging said keyway when inwardly depressed, said keyway having a top face curved to the curvature of the bore of the front head for contact therewith, there being a depressed seat in said top face for registry with said hole, a spring outwardly urging said key, a ball normally confined in said hole so as to be urged into the bore of said front head to engage said seat and depress the key, and means for effecting such displacement of the ball from the hole whereby it is caused to travel around the bore of the front head in the rotation of the chuck to maintain the key in depressed position. 10

6. The combination in a pneumatic drill, of a front head having its bore interrupted by a hole, a chuck journalled in said bore and having a bore receptive to a steel, said chuck also having a radial slot leading inwardly to its bore and circumferentially enlarged at its outer end, said chuck also having recesses extending inwardly from the enlarged outer end of the slot, a key radially slidible in said slot for retaining a steel in the bore of the chuck, said key having wings 30 disposed in the enlarged outer end of the slot and having an incurvate back for engaging the bore of the front head, said back having a spherical seat for registry with said hole, compression springs seated in said recesses and shouldered 35 against said wings to urge the key outwardly, a ball normally confined in said hole so as to be urged into the bore of the front head to engage said spherical seat and depress the key, and means for effecting such displacement of the ball 40 whereby it is caused to travel around the bore of the front head in the rotation of the chuck to maintain the key in depressed position.

7. A structure as defined in claim 3, in which the means for effecting displacement of the ball 45 from the hole consists of a manually operable keeper slidible in the hole and provided with a device by which it is releasably locked to close the hole.

8. The combination in a pneumatic drill, of a front head having its bore interrupted by a hole, a chuck journalled in said bore and having an axial bore receptive to a steel, a depressible key mounted in said chuck in alignment with said hole for retaining said steel, said key having a depressed seat for registry with said hole, a ball normally confined in said hole so as to be urged into the bore of said front head to engage said seat and depress the key, and means for effecting such displacement of the ball from the hole 60 whereby it is caused to travel around the bore of the front head in the rotation of the chuck to maintain the key in depressed position, said means consisting of a keeper having a shank slidible in the hole with an inner end face for abutting the ball and lying flush with the bore of the front head when the keeper is shifted to an inner position, and a bayonet slot mechanism for releasably securing the keeper in said inner position. 65

VICTOR KARL NELSON.
